DESIGN FOR A CANNED BEVERAGE SERVER

Louis G. Weigel, Roselle, N. J.

Application July 18, 1936, Serial No. 63,921

Term of patent 3½ years

To all whom it may concern:

Be it known that I, Louis G. Weigel, a citizen of the United States, residing at Roselle, county of Union, and State of New Jersey, have invented a new, original, and ornamental Design for a Canned Beverage Server, of which the following is a specification, reference being had to the accompanying drawing, forming part thereof.

I claim:

The ornamental design for a canned beverage server, as shown.

LOUIS G. WEIGEL.
